(57) **CLAIM**

The ornamental design for a portable drill, battery, adapter, and battery pouch set as shown and described.

DESCRIPTION

FIG. 1 is a front perspective view of the portable drill of the portable drill, battery, adapter, and battery pouch set of the invention;

FIG. 2 is a front elevation view thereof;

FIG. 3 is a top plan view thereof;

FIG. 4 is a side elevation view thereof, the other side being a mirror image;

FIG. 5 is a rear elevation view thereof;

FIG. 6 is a bottom plan view thereof;

FIG. 7 is a front perspective view of the battery of the portable drill, battery, adapter, and battery pouch set;

FIG. 8 is a rear elevation view thereof;

FIG. 9 is a top plan view thereof;

FIG. 10 is a side elevation view thereof, the other side being a mirror image;

FIG. 11 is a front elevation view thereof;

FIG. 12 is a bottom plan view thereof;

FIG. 13 is a front perspective view of the adapter of the portable drill, battery, adapter, and battery pouch set;

FIG. 14 is a rear elevation view thereof;

FIG. 15 is a top plan view thereof;

FIG. 16 is a front elevation view thereof;

FIG. 17 is a side elevation view thereof, the other side being a mirror image;

FIG. 18 is a bottom plan view thereof;

FIG. 19 is a front perspective view of the portable drill, battery, and adapter of the portable drill, battery, adapter, and battery pouch set shown partially assembled for illustration purposes;

FIG. 20 is a perspective view of the battery pouch of the portable drill, battery, adapter, and battery pouch set;

FIG. 21 is a rear elevation view thereof;

FIG. 22 is a top plan view thereof;

FIG. 23 is a side elevation view thereof, the other side being a mirror image;

FIG. 24 is a front elevation view thereof; and,

FIG. 25 is a bottom plan view thereof.

The alternating long and short broken lines in the FIGS. 13, 14, 15, 16, 17, 18, and 19 views indicate the order of assembly of the components of the portable drill, battery, adapter, and battery pouch set, and form no part of the claimed design. Additionally, the cords in the same views are shown broken away in order to indicate that a specific length of cord is not part of the claimed design. It is furthermore noted that the short broken lines indicating the point at which the cords are shown broken away form no part of the claimed design.
